UNITED STATES PATENT OFFICE

2,089,161

CONTROL SYSTEM

Willis H. Gille, St. Paul, Minn., assignor to Minneapolis-Honeywell Regulator Company, Minneapolis, Minn., a corporation of Delaware

Application June 3, 1936, Serial No. 83,241

10 Claims. (Cl. 172—239)

My invention relates to a new control system and more particularly to one of the class employing a relay switch between a main control switch and a device to be actuated.

5 An object of the present invention is to provide a control system wherein a switch operating means is initially connected in series with a motor to be operated, the circuit having sufficient impedance so that only the switch operating means is brought into operation, and in which upon said switch operating means being brought into operation a new circuit having a relatively low impedance is established to the motor and wherein means are provided for interrupting said circuit after a predetermined movement of said motor.

A further object of the present invention is to provide a control system of the type just mentioned wherein the new circuit that is established to the device to be actuated shunts out the switch actuating means so as to deenergize the same and wherein means are provided for holding the switch in the position to which it has been moved by the energization of said actuating means.

25 A further object of the invention is to provide a control system employing a control switch movable between two contact making positions in control of a motor operated device which is operated between two positions and electrically 30 operated circuit changing means wherein upon said control switch moving to either of its two contact making positions a circuit is first established to the motor operating said device through said circuit changing means and upon the resultant operation of said circuit changing means 35 to a circuit which is independent of said control switch.

A further object of the present invention is to provide a control system of the type set forth in the previous object in which the circuit changing means consists of two electromagnetic coils and a switch movable between two contact making positions.

Other objects of the invention will be apparent 45 from a consideration of the accompanying specification, claims and drawing, of which

Figure 1 is a front elevational view partly in section of a relay particularly designed for use with my new control system;

50 Figure 2 is a sectional view of the relay structure with a section taken along the line 2—2 and in a direction of the arrows indicated thereon;

Figure 3 is a schematic view of one form of my 55 control system, and

Figure 4 is a schematic view of a modified form of my control system.

Referring to the drawing, the relay proper which is used in the new control system on the present invention is indicated in Figures 1 and 2. 5 This relay is of a somewhat similar structure to that shown in my co-pending application, Serial No. 758,231, filed December 19, 1934. A primary difference between the relay of my previous application and the present relay is that 10 in the previous relay the contact arm was biased to a mid position so that when the two coils are balanced, either through both being energized or both being deenergized, the contact arm was in mid position, whereas in the present relay the 15 spring associated with the contact arm has an over-center snap action so that the contact arm is in engagement with one or the other of the contacts depending upon which direction the coils have been unbalanced during the previous operation of the relay. 20

Referring to Figure 1 of the drawing, the two coils of the relay are generally designated by the reference numerals 11 and 12. The structure of these coils is shown in connection with a 25 sectional representation of coil 11. In this respect, the winding of coil 11 is designated by the reference numeral 14. Extending through this winding is a tubular sleeve 15 of non-magnetic metal. Engaging each end of the winding 30 14 are end plates 16, which end plates are held in engagement with the winding by overturned edges 17 of the tubular sleeve 15. The coils 11 and 12 are mounted in a relay casing 20, which casing extends over the top of the coils and is provided at its bottom extremities with 35 overturned fingers 21 which serve to hold the coils 11 and 12 in position. Extending through casing 20 is a pivoted pin 22 and pivotally mounted on this pin is an armature member generally designated 40 by the reference numeral 25. This armature member is pivotally mounted on the pin 22 through downwardly extending ears 26. The armature 25 is provided at its outer ends with 45 downwardly extending portions 28, which portions extend into the openings of the coil 11 and constitute cores therefor. Secured to the armature 25 is a downwardly extending contact arm 30, which contact arm carries adjacent its lower end oppositely disposed contacts 31 and 32. Contacts 31 and 32 are adapted to cooperate with 50 stationary contacts 33 and 34, respectively.

It will be readily seen from the foregoing description and from a consideration of the drawing that in the event that coil 12 is energized 55

and coil 11 is not, contact arm 30 will be moved to assume the position shown in the drawing wherein contacts 31 and 33 are in engagement. If on the other hand, coil 11 is energized and coil 12 is not, the core portion 28 cooperating with coil 11 will be drawn downwardly moving the switch arm 30 into opposite position such that contacts 32 and 34 are in engagement. In this respect, the structure in action of the relay of the present invention is identical with that set forth in my previous application referred to above, which application may be referred to for further details of construction not shown or described in the present application.

15 As distinguished from the relay of my previous application, the armature 25 of the present relay is provided with an upwardly extending portion 35, which portion is provided at its upper extremity with a forwardly extending lug 36. Over this lug is secured one end of a spring 38, which spring extends through any suitable opening in the armature 25. The lower end of the spring 38 is secured to an inwardly extending ear 40 which forms an integral part of casing 20. 20 It will be noted that the spring is secured to the casing and to the armature upon opposite sides of the pivot pin 22 so that upon contact arm 30 being moved slightly beyond center position in either direction, the spring 38 is effective to continue to move the armature and contact arm in that direction. Moreover, upon the coils being so unbalanced that contact arm 30 is moved into engagement with either one or the other of the contacts 33 and 34, spring 38 25 will act to retain the contact arm 30 in this position. Moreover, the spring 38 will function in the usual manner of an over-center snap action spring to give a quick make and break action thus eliminating sparking between the contacts 30 associated therewith.

40 In Figure 3, I have illustrated one form of my control system as applied to a temperature control system. The device to be controlled in this case is a fuel valve which is generally designated by the reference numeral 50. This valve 45 may be of any conventional type, preferably of one of the types shown in the patent to George D. Bowers No. 1,861,046 issued May 31, 1932. As shown in the drawing, this figure comprises a valve casing 51 having the usual transverse partition 52 extending therethrough. This partition 52 is apertured in the usual manner to provide a valve opening against which is seated a valve head 53, which in the present instance is shown as being spherical in form, although it is 50 to be understood that this plays no part whatsoever in my invention. Secured to the valve head 53 is a valve stem 55 consisting of upper and lower sections of non-magnetic material between which is a member 56 of magnetic material constituting the core of a solenoid actuator for the valve. The upper section of stem 55 terminates in a reduced portion 57 on which is threaded a nut 58. Associated with the core 56 are two 55 solenoid windings 59 and 60. Upon the energization of winding 59, the core 56 is moved in a direction tending to center the core with respect to the winding 59 which direction is such as to move valve 53 away from its seat. When it is desired to close the valve again, winding 60 is 60 energized to move the core 56, and consequently the valve 53, in a reverse direction.

70 In order to deenergize winding 59 after the valve has been opened and in order to retain the 75 valve in its open position after the winding 59

has been deenergized, a combination cycling switch and valve retaining mechanism is provided, which mechanism is generally indicated by the reference numeral 64. This mechanism comprises a snap disc 65 which is provided with an aperture in its central portion through which the reduced portion 57 of stem 55 extends. The disc member 65 is also provided with diametrically oppositely disposed apertures 68 and 69. Cooperating with disc member 65 are contact structures 70 and 71. The contact structure 70 comprises two end metallic contact members 73 and 74 which are secured together through a reduced portion 75 of insulating material, which portion extends through the aperture 68 in disc member 65. The contact structure 71 comprises two end metallic members 78 and 79, which members are secured together through a center portion 80 which, in this case, is of conducting material. The portion 80 extends through aperture 69 in a manner similar to that in which portion 75 extends through aperture 68. Due to the fact that the center portion of disc 65 is deformed, disc member 65 tends to be bowed in either one direction or the other depending upon the position to which it is moved by the action of the solenoid mechanism and will be moved between these positions with a snap action. Moreover, through its cooperation with contact structures 70 and 71, the disc 65 acts as a switch. It will be observed that in the position shown in the drawing in full lines, which position corresponds to the closed position of valve 50, the disc 65 acts to connect the contact structure 71, which, unlike structure 70, is electrically continuous, with the contact member 74. In this position of the disc, it does not engage with contact member 73. When the solenoid is so energized, the stem 55 is moved upwardly snapping the disc 65 into the position shown in dotted lines 40 in Figure 3 wherein the disc engages contact member 73 but not contact member 74. The disc then acts to connect the contact structure 71 with the contact member 73. Moreover, due to the snap action of the disc 65, the disc tends to remain in the dotted line position when so moved to such an extent that it will retain the valve 53 above its seat against the action of gravity. Thus, as will be readily seen, the disc 65 serves a dual function of acting as a switch member and 45 also acting to retain the valve in the position to which it is moved through the energization of the solenoids. The operation of this valve will be more apparent from a subsequent description of the operation of my system.

50 The controlling switch which may be of any desired form is shown in the drawing as consisting of a thermostat 80. This thermostat may be of any desired form but for the purposes of illustration is shown as comprising a bimetallic element 81 to which is attached a contact arm 82. This contact arm 82 carries contacts 83 and 84 which are adapted to be moved into engagement with contacts 85 and 86, respectively.

55 A step-down transformer is employed to supply power for the operation of my control system, this step-down transformer being generally indicated by the reference numeral 100. This transformer comprises a line voltage primary 101 which is connected to suitable line wires 102. 70 This transformer 100 also comprises a core 102 and a low voltage secondary 103.

75 The relay proper is shown somewhat schematically in this figure but inasmuch as the same reference characters are applied in a more de-

talled showing in Figures 1 and 2, it is deemed unnecessary to further describe this relay in the present figure.

It will be understood that the valve 50 may be employed to control the supply of fuel to any desired type of fuel burner, such as a gas burner. With the parts in the position shown in the drawing, the temperature of the device which is to be controlled is within the desired range of values. Under these conditions, the valve 50 is closed and no fuel is being supplied to the burner. Upon the temperature of the space being controlled falling below a desired value, the bimetallic element 91 is effective to move contact arm 92 in a direction to cause engagement of contacts 93 and 95. Upon this taking place, the following circuit is established to relay coil 11: from the right-hand terminal of secondary 103 through conductors 106 and 107, bimetallic element 91, contact arm 92, contacts 93 and 95, conductor 109, relay coil 11, conductors 110 and 111, solenoid winding 59, conductor 112, contact member 74, disc 65, contact member 79, and conductor 113 to the left-hand terminal of secondary 103. It will be noted that in the circuit just traced the coil 11 of the relay and the solenoid winding 59 are connected in series. Since the work performed by the coils 11 and 12 is relatively small compared with that performed by solenoid windings 59 and 60, the energy required by coils 11 and 12 for operation of the relay is relatively low as compared with that required by solenoid windings 59 and 60 for operation of the valve. Moreover, because of the low current requirement of the coils 11 and 12, these coils may have a much higher impedance than the solenoid windings. In the circuit just traced, as previously stated, these two devices are connected in series so that the resistance of coil 11 prevents sufficient energy from being supplied to winding 59 to actuate the same. The relatively small amount of current flowing through the circuit just traced, however, is sufficient to energize coil 11 with the result that contact arm 30 is moved towards the right in a direction such as to cause engagement of contacts 32 and 34.

Upon the engagement of contacts 32 and 34, the following circuit is established to solenoid winding 59: from the right-hand terminal of secondary 103 through conductors 106 and 115, contact arm 30, contacts 32 and 34, conductors 116 and 117, solenoid winding 59, conductor 112, contact member 74, disc 65, contact member 79 and conductor 113 to the left-hand terminal of secondary 103. It will be noted that the new circuit does not include the winding 11 and, furthermore, is independent of thermostat 90.

The new circuit, because of the elimination of coil 11, is of such low impedance that sufficient power is supplied to solenoid winding 59 for the actuation of valve stem 55. Furthermore, the new circuit constitutes a shunt across the coil 11 and as a result effectively deenergizes the same. In addition, the new circuit is independent of the thermostat 90 so that the thermostat 90 is not only freed from excessive current load on its contacts such as is necessary for the operation of device 59, but, moreover, the operation of the valve to open position is independent of the thermostat so that it is impossible for the operation of the valve to be terminated in a mid position by reason of the thermostat 90 being momentarily deflected so as to cause a temporary disengagement of contacts 92 and 93. These latter two features are of considerable importance

inasmuch as it has been found that the control of a device such as the valve 50 directly from the thermostat is highly unsatisfactory both from the standpoint of the excessive current load necessary for the thermostat to carry and from the standpoint of the unstable contact making position of the thermostat. With the control system of the present invention, the only time that the main motor winding 59 is connected in series with the thermostatic contacts, the relatively high resistance relay winding 11 is also in the circuit so that current flowing through the same has such a small value that the thermostatic contacts are entirely capable of carrying the same. 15

Upon the solenoid winding 59 being energized in the manner previously explained, core 56 is moved upwardly, also in a manner previously explained. The result is that disc 65 is snapped over-center, which action serves to move the left-hand portion of disc 65 away from contact member 74 and into engagement with contact member 73, thus breaking the previously traced circuit to solenoid winding 59. At the same time, the upward snapping of disc 65 serves to hold the valve 53 away from its seat upon deenergization of winding 59. This action is more fully set forth in the Bower patent previously referred to and for a more full understanding of the action of the same, reference is made to that patent. 30

Upon the valve 50 being moved away from its seat in the manner described, fuel is supplied to the burner, or other heat producing device. Sooner or later, the temperature of the space to be controlled is raised sufficiently to cause bimetallic element 91 to be heated to the point where contact arm 92 is moved to the right sufficiently to cause engagement of contacts 94 and 96. Upon this taking place, the following circuit is established to relay coil 12: from the right-hand terminal of secondary 103 through conductors 106 and 107, bimetallic element 91, contact arm 92, contacts 94 and 96, conductor 118, relay coil 12, conductors 119 and 120, solenoid winding 60, conductor 121, contact member 73, 45 disc member 65, contact member 78, contact member 79 and conductor 113 to the left-hand portion of secondary 103. It will be noted that in the circuit just traced, the relay coil 12 and the solenoid winding 60 are connected in series 5 in a manner similar to the way in which relay coil 11 and solenoid winding 59 were connected in the first circuit which was traced in the description of the operation of this system. As in the previous case, the presence of the resistance of 5 relay coil 12 in the circuit prevents sufficient current from being supplied to winding 60 to cause actuation of valve stem 55 against the biasing action of spring 65. Also as in the previous case, the current flowing through the circuit is sufficient to energize coil 12 to the point where it is effective to move contact arm 30 to the left against the action of biasing spring 38 so as to cause engagement of contacts 31 and 33. 60

The engagement of contacts 31 and 33 causes 65 the following circuit to be established to solenoid winding 60: from the right-hand terminal of secondary 103 through conductors 106 and 115, contact arm 30, contacts 31 and 33, conductors 122 and 120, solenoid winding 60, conductor 70 121, contact member 73, disc member 65, contact structure 71, and conductor 113 to the left-hand terminal of secondary 103. It will be noted that the last traced circuit does not include the relay coil 12 and is independent of the ther- 75

mostat 90. In this respect, the action is identically the same as that described in connection with the energization of solenoid winding 59.

The energization of solenoid winding 60 causes core 56 to be moved downwardly against the biasing action of disc 65 causing disc 65 to be snapped over-center with the result that valve 53 is moved to the closed position shown in the drawing, in which position it is held by the action of disc 65. At the same time, the previously traced circuit through winding 60 is interrupted through the left-hand portion of disc 65 moving away from contact member 73 and into engagement with contact member 74. The engagement of disc 65 with contact member 74 does not, however, cause the establishment of any circuit inasmuch as contact 93 is not in engagement with contact 95 nor is contact 32 in engagement with contact 34. The system is, accordingly, not again placed in operation until the temperature again falls to the point where contacts 93 and 95 will move into operation whereupon the previously described cycle of operation is repeated.

It will be readily seen from the foregoing description, that by the use of my improved control system it is possible to operate a device having a rather large current demand with a control switch which has a relatively low current carrying capacity and whose contact making positions are unstable. It will furthermore be seen that this is accomplished through an extremely simple and relatively inexpensive apparatus. Moreover, as previously indicated, while I have described my control system in Figure 3 as applied to temperature control, it is obvious that it may be applied to any type of a control system for an electrically actuated device. Furthermore, the system is of broader application than where the control switch is of any particular type. Moreover, while I have shown the device to be operated as of being of a well known type, which in effect employs two motors, one for operating the device in one direction and the other for operating the device in the other direction, it will be understood that the system may well be applied to any other motor operated device, which is successively actuated between two positions. Thus in Figure 4, the control system which forms the inventive subject matter of the present application is applied to the control of a somewhat different type of motor operated device.

Referring to said figure, a portion of a furnace is designated by the reference numeral 125. This furnace may be of any desired construction and may be provided with as many different draft controls as is customary in the art. However, since the particular construction of the furnace and the particular draft control arrangement forms no part of the present invention, only the draft damper 126 is disclosed. This draft damper is pivotally mounted in the usual manner and biased to a closed position.

Connected to the damper 126 is a chain 128, or other suitable flexible connecting member which is connected at its opposite end to a crank arm 129 of a shaft 130. This shaft constitutes a main shaft of a damper motor unit generally designated by the reference numeral 131. The motor proper of the damper motor unit 131 comprises a rotor 132 and a field winding 133. The rotor 132 drives the shaft 130 through a suitable reduction gearing 135.

Secured to the shaft 130 is a cam 136 which is designed to actuate a switch blade 137. The switch blade 137 is provided with a cam follower

portion 138 and cooperates with two contacts 139 and 140. The cam 136 is provided over 180 degrees of its circumference with a raised toe portion 142. The relation of the various parts is such that when the cam follower 138 is in engagement with the raised portion of the cam 136, switch blade 137 is in engagement with contact 139. On the other hand, when the cam follower 138 is in engagement with the depressed portion of the cam surface of cam 136, the switch blade 137 is in engagement with contact 140. Thus it will be seen that switch blade 137 is in engagement with contact 139 for 180 degrees of rotation of shaft 130 and in engagement with contact 140 for the other 180 degrees of rotation of shaft 130. The position of the cam with respect to crank arm 129 is such that switch arm 137 is moved from one contact to another when crank arm 129 reaches its uppermost and lowermost position, respectively. These positions of crank arm 129, as will be obvious from the drawing, correspond to the closed and open positions of damper 126. The switch blade 137 and its associated contacts accordingly function as a cycling switch to terminate the operation of the motor at the end of each cycle.

A step-down transformer is employed to supply power for the operation of the system. This transformer comprises a line voltage primary 150 which is connected to line wires 151. The transformer also comprises a core 152 and a low voltage secondary 153.

Inasmuch as the thermostat may be the same in construction as that of Figure 3 and since its operation is in no respect different from that of Figure 3, the same reference characters have been applied to this thermostat as to the corresponding thermostat in Figure 3. Moreover, the same reference characters are also applied to the relay as are applied to this device in the previous figures.

With the parts in the position shown in Figure 4, the temperature of a space in which thermostat 90 is located is within the range of the temperature desired to be maintained. The draft damper 126 is, accordingly, closed so that the furnace 125 is supplying a minimum amount of heat. The arrangement of bimetallic element 91 with respect to contact arm 92 is such that upon a decrease in temperature the arm 92 is deflected to the left. If such a decrease does occur in the room, as is likely in view of the closed position of damper 126, contact arm 92 will be moved sufficiently to the left to cause engagement of contacts 93 and 95. When this occurs, the following circuit will be established to relay coil 11: from the right-hand terminal of secondary 153, through conductors 160 and 161, bimetallic element 91, contact arm 92, contacts 93 and 95, conductor 162, relay coil 11, conductors 163 and 164, contact 139, switch arm 137, conductor 165, motor field winding 133 and conductor 166 to the left-hand terminal of secondary 153.

It will be noted that in the circuit previously traced the relay coil 11 and the motor winding 133 are connected in series. Due to the fact that the relay coil 11 requires a relatively low current consumption for operation thereof, sufficient power will be supplied to the relay coil 11 for operation thereof but insufficient power will be supplied to the motor winding to cause operation of the motor. This action is exactly similar in this respect to that shown in Figure 3 and the advantages of this feature are substantially the same as set forth in connection with Figure 3.

The energization of relay coil 11 causes the left-hand core 28 to be drawn downwardly rotating the armature in a counter-clockwise direction and causing contacts 32 and 34 to be moved into engagement. As soon as this is done, the following circuit is established to the motor field winding 133: from the right-hand terminal of secondary 153, through conductors 160 and 168, contact arm 30, contacts 32 and 34, conductors 169 and 164, contact 139, switch arm 137, conductor 165, field winding 133 and conductor 166 to the left-hand terminal of secondary 153. It will be noted that in this new circuit both the thermostat 90 and the relay coil 11 are shunted out. This will result in insuring that the motor will continue to operate even though there is a momentary separation of thermostat contacts 93 and 95. Moreover, the circuit just traced is of sufficient low impedance that the motor will be supplied with sufficient energy to operate in a normal manner. The result will be that the shaft 130 will be rotated in a direction indicated by the arrow adjacent cam 136 causing crank arm 129 to move damper 126 to an open position. This rotation will continue until crank arm 129 reaches a substantially vertical position, at which time the cam follower 138 will ride off of the raised portion of cam 136 causing the switch arm 137 to separate from the contact 139 and move into engagement with contact 140. When this occurs, the previously traced motor circuit will be interrupted through the separation of switch blade 137 from contact 139 so that the operation of the motor is terminated leaving crank arm 139 in a vertical position.

As a result of the previous operation, the damper is placed in its full open position with the result that the furnace is delivering heat at a much more rapid rate than previously. The result of this is that the temperature in the space heated by the furnace, in which the thermostat is located, will normally soon rise to such a value as to cause switch arm 98 to be deflected sufficiently to the right to cause engagement of contacts 94 and 96. When this occurs, the following circuit will be established to relay coil 12: from the right-hand terminal of secondary 153, through conductors 160 and 161, bimetallic element 91, contact arm 92, contacts 94 and 96, conductor 171, relay coil 12, conductor 172, contact 140, switch arm 137, conductor 165, motor field winding 133 and conductor 166 back to the left-hand terminal of secondary 153. It will be noted that in the circuit just traced the relay coil 12 is connected in series with the field winding 133. This operates in a manner similar to that set forth in the previous cases to restrict the flow of current through the circuit to a value which is just sufficient to operate the relay but is insufficient to either harm the thermostat contacts or cause operation of the motor.

The energization of relay coil 12 causes the armature to be rotated in a clockwise direction so that the parts assume the position shown in Figure 4 wherein contacts 31 and 33 are in engagement. This causes the following circuit to be established: from the right-hand terminal of secondary 153, through conductors 160 and 168, contact arm 30, contacts 31 and 33, conductor 174, contact 140, switch arm 137, conductor 165, field winding 133, and conductor 166 to the left-hand terminal of secondary 153. With the establishment of the new circuit, the relay coil 12 and the thermostat 90 are shunted out in a manner similar to that in connection with the pre-

viously described operation of the system so that the motor 133 is supplied with sufficient power for operation. The result is that shaft 130 is again rotated in the direction of the arrow adjacent cam 136 causing the crank arm to be lowered and closing damper 126. This rotation continues until crank arm 129 is in substantially its lowermost position at which time cam follower 138 will ride up on the left portion 142 of cam 136 causing a separation of switch blade 137 from contact 140 and engagement of the switch blade with contact 139. This will terminate operation of the motor until the thermostat 90 again "calls for heat", or in other words, until contacts 93 and 95 are again moved into engagement. The parts will then be in the position shown in the drawing and upon such engagement of the thermostatic contacts, the described cycle of operation will be repeated.

From the described operation of Figures 3 and 4, it will be obvious that my control system is readily applicable to a variety of electrically operated devices. It will furthermore be seen that the device of the control system wherein it is possible to control a device using a rather large amount of current for operation with a switch which is either unstable in its contact making position or is unadapted to carry large currents, or both. It will furthermore be seen that I have devised a simple and compact relay structure for use with my control circuit.

While I have shown certain specific embodiments of my invention, it is to be understood that these are for purposes of illustration only and that my invention is to be limited only by the scope of the accompanying claims.

I claim as my invention:

1. In a control system, an electrically operated motor, a switch, electromagnetic operating means for said switch requiring a lesser amount of energy for operation than said motor, a source of energy, means for establishing a circuit connecting said motor and said electromagnetic operating means with said source of energy, said circuit having a sufficiently high impedance that only said electromagnetic operating means is brought into operation to move said switch into a circuit making position, means effective upon said switch being moved into said circuit making position to establish a circuit to said motor of sufficiently low impedance to cause operation of said motor, and means operative to interrupt said last named circuit after a predetermined movement of said motor.

2. In a control system, an electrically operated motor, a switch, electromagnetic operating means for said switch requiring a lesser amount of energy for operation than said motor, a source of energy, means for establishing a circuit connecting said motor and said electromagnetic operating means with said source of energy, said circuit having a sufficiently high impedance that only said electromagnetic operating means is brought into operation to move said switch into a circuit making position, means to retain said switch in said circuit making position independently of said operating means, means effective upon said switch being moved into said circuit making position to establish a circuit to said motor of sufficiently low impedance to cause operation of said motor and to deenergize substantially said operating means, and means operative to interrupt said last named circuit after a predetermined movement of said motor.

3. In a control system, electrically operated

motor means requiring a relatively large amount of energy for operation, a control switch movable between first and second contact making positions, a second switch, first and second electromagnetic operating means therefor, said first operating means being effective when energized to move said second switch into a first contact making position and said second operating means being effective when energized to move said second switch into a second contact making position, both of said operating means requiring a relatively small amount of energy for operation, a source of energy, means operative upon said control switch being moved into said first contact making position to establish a circuit connecting said motor means and said first electromagnetic operating means with said source of energy, said circuit having a sufficiently high impedance that only said first electromagnetic operating means is brought into operation to move said second switch into said contact making position, yieldable means to retain said second switch in said position when so moved, means effective upon said second switch being so moved to establish a circuit to said motor means independently of said control switch and of sufficiently low impedance to cause movement of said motor means, switching means effective to interrupt said circuit upon a predetermined movement of said motor means, means effective upon said control switch being moved to said second circuit making position to establish a circuit between said source of energy and said second electromagnetic operating means to move said second switch into said second contact making position and circuit means effective upon such movement of the second switch to cause said motor means to be reenergized.

4. In a condition control system, a condition responsive switch movable between two contact making positions corresponding to low and high values of said condition, condition changing means, an electrically operated controlling means therefor adapted to be moved between a position in which said condition changing means is effective to change the value of the condition in one direction and a position wherein the value of the condition tends to vary in the other direction, a circuit changing means requiring a relatively small amount of energy for operation thereof, means effective upon said condition responsive switch being moved to either contact making position to cause a circuit to be established from said source of energy to said controlling means through said circuit changing means, said circuit having a sufficiently high impedance that only said circuit changing means is brought into operation, and means effective upon such operation of said circuit changing means to establish a circuit to said controlling means independently of said condition responsive switch and of sufficiently low impedance as to cause operation of said controlling device from one to the other of its two positions.

5. In a control system, a control switch movable between two contact making positions, a device to be operated between two positions, electrical motor means for operating said device, electrically operated circuit changing means requiring a lesser amount of energy for operation than said motor means, a source of electrical energy, and means effective upon said control switch being moved to either contact making position to cause a circuit to be established from said source of energy to said motor means

through said circuit changing means, said circuit having a sufficiently high impedance that only said circuit changing means is brought into operation, and means effective upon such operation of said circuit changing means to establish a circuit to said motor means independently of said control switch and of sufficiently low impedance as to cause operation of said motor means from one to the other of its two positions.

6. In a control system, a control switch movable between two contact making positions, a device to be operated between two positions, electrical motor means for operating said device, electrically operated circuit changing means requiring a lesser amount of energy for operation than said motor means, a source of electrical energy, and means effective upon said control switch being moved to either contact making position to cause a circuit to be established from said source of energy to said motor means through said circuit changing means, said circuit having a sufficiently high impedance that only said circuit changing means is brought into operation, means effective upon such operation of said circuit changing means to establish a circuit to said motor means independently of said control switch and of sufficiently low impedance as to cause operation of said motor means from one to the other of its two positions, cycling switching means, means for moving said switching means between two contact making positions in accordance with the movement of said device between its said two positions, and means including said switching means for cooperating with said previously named apparatus for causing said motor means to so operate as to move said device in one direction upon said control switch being moved into one contact making position and in the opposite direction upon said control switch being moved into its other contact making position.

7. In a control system, a control switch movable between two contact making positions, a device to be operated successively between two positions, a pair of electric motor means, one to cause operation of said device in each direction, a relay comprising a pair of relay coils and a switch movable between two contact making positions by the respective energization of said coils, a source of electrical energy and circuit means operable upon said control switch being moved to either contact making position to establish an energizing circuit to one of said relay coils through one of said motor means to cause said relay switch to be moved from one to the other of its contact making positions, said circuit means being effective upon said relay switch being so moved to establish an energizing circuit to said one motor means independently of said one relay coil.

8. In a control system, a control switch movable between two contact making positions, a device to be operated successively between two positions, a pair of electric motor means, one to cause operation of said device in each direction, a relay comprising a pair of relay coils and a switch movable between two contact making positions by the respective energization of said coils, a source of electrical energy and circuit means operable upon said control switch being moved to either contact making position to establish an energizing circuit to one of said relay coils through one of said motor means to cause said relay switch to be moved from one to the other of its contact making positions, said circuit means

being effective upon said relay switch being so moved to establish an energizing circuit to said one motor means independently of and shunting said one relay coil.

5. 9. In a control system, a control switch movable between two contact making positions, a device to be operated successively between two extreme positions, a pair of electric motor means, one to cause operation of said device in each 10 direction, a relay comprising a pair of relay coils and a switch movable between two contact making positions by the respective energization of said coils, a source of electrical energy, circuit means operable upon said control switch being 15 moved to either contact making position to establish an energizing circuit to one of said relay coils through one of said motor means to cause said relay switch to be moved from one to the other of its contact making positions, said circuit means being effective upon said relay switch being so moved to establish an energizing circuit to said one motor means independently of said one relay coil, and switching means effective to interrupt both of said circuits upon said device reaching the extreme position to which it is 20 moved as the result of the energization of said motor means.

10. In a condition control system, condition

changing means, control means, control means movable from a position in which the value of the condition is increased to a position wherein the value of the condition is decreased, motor means for moving said control means between 5 said two positions, a condition responsive switch movable between two contact making positions, a relay comprising a pair of relay coils and a switch movable between two contact making positions upon the respective energization of said coils, 10 a source of electrical energy, circuit means effective upon the condition responsive switch moving to one of said two contact making positions to establish an energizing circuit to one of said relay coils through said motor means to 15 cause said relay switch to be moved from one to the other of its contact making positions, said circuit means being effective upon said relay switch being so moved to establish a circuit to said motor means independently of said relay coil, 20 and switching means operated by said motor to terminate operation of said motor upon said control means reaching one of said positions until said condition has changed sufficiently to cause said condition responsive switch to assume the 25 other of its contact making positions.

WILLIS H. GILLE.
